UNITED STATES PATENT OFFICE.

WILFRED ROTHERY WOOD, OF LONDON, ENGLAND.

CHAIN GRATE FOR FURNACES.

Application filed April 27, 1923, Serial No. 635,045, and in Great Britain April 27, 1922.

This invention relates to that form of chain grate stoker in which the joints of alternate rows of links are staggered, this form having advantages over that in which the joints are in line with each other in transverse rows.

The object of the invention is to provide a grate of this form in which the links are engaged with the pins by means of slots 10 in the links and in which a link cannot be disengaged while the chain is straight or slightly curved but can be disengaged when the curvature is sufficient, as when the chain is passing over the drum.

For this purpose the link is of the kind 15 in which the slots are of such form that their open ends lie between lines drawn through the axes of the pins at right angles to the length of the chain while their closed 20 ends are outside these lines, and are in such position relatively to the ends of the link that when the links are engaged with the pins in the straight chain their ends substantially butt against each other.

When removal of a link is necessary the 25 chain is brought into such a position that the link in question is on the front surface of the front drum and the links in the transverse row on each side of the row containing 30 the link to be removed are forced towards each other by pressure applied to their ends by a suitable device such as a clamp; the link in question can now be removed.

The application of this end pressure is 35 facilitated by a flat surface on each end of the link.

The slotted link of this invention may be 40 shaped to afford air spaces between them but there is considerable advantage in stamping the links from steel sheet of uniform thickness. A steel link may be made comparatively very thin so that a larger 45 number of them than of cast iron links can be contained in a given width of grate and the air spaces can be correspondingly more numerous.

One form of link according to the invention 50 is slightly bent either during the stamping or as a separate operation. Thus the links may be in actual contact with each other and yet afford the necessary air spaces so that distance pieces or bosses may be avoided.

One of the factors in determining the 55 dimensions of the links of a chain grate is the amount of surface presented by the link

to the cooling effect of the air passing between the links; if this surface is insufficient the chain becomes too hot. For a given number of air spaces a certain depth of link 60 is necessary in order that the chain may be sufficiently cooled. In the case of cast iron links the strength of the material is not sufficient to permit of a thin link; it follows, therefore that a shallower link than that 65 commonly used is hardly feasible.

By the present invention the weight of a chain grate is considerably reduced by constructing the steel links of small width and small depth as compared with the usual cast 70 iron links. As already pointed out the small width determines a great number of air-spaces, so that the depth of the link may be diminished more than enough to make the weight of the chain less than that of a cast 75 iron chain providing the same aggregate air space, notwithstanding the greater number of links.

Another advantage of a chain grate having 80 numerous narrow air spaces rather than a few wider spaces is that the amount of riddlings passing through the grate is much reduced.

In the accompanying drawings, Fig. 1 is a 85 vertical section through a drum carrying one end of a chain grate stoker and Fig. 2 is a part plan of the chain grate.

The links *a* are carried by the pins *b* which have at each end a suitable head to prevent the links from slipping laterally 90 from the pins. The engagement of the links with the pins is by means of the slots *c* which incline towards each other as shown. The links in each longitudinal row break 95 joint with the links on the row on each side of them. It will be noted that a link can be lifted from the pins which engage it only when the pins are caused to approach each other; this is possible only when the chain travels round the drum and the adjacent 100 ends of the links are thereby moved away from each other. By stopping the drum and forcing towards each other the links which have been moved apart in two successive transverse rows, the pins engaging these 105 links may be made to approach each other sufficiently to allow the operator to lift from the pins the links which alternate with the first-named links.

A tool suitable for compressing the chain 110 in this manner is a curved clamp *d*, the jaws *e* of which are pivoted to its body and are

long enough to extend over several longitudinal rows of links. Assuming that link α^3 is to be removed, the jaws are applied to the ends of links α' , α^2 and the screw f is turned to bring the jaws nearer together. It then becomes possible to lift link α^3 from its place.

The under surface of each link is formed with a recess, leaving a tooth g adapted to engage teeth h on the drum which extend along the periphery parallel to the axis.

As shown in Fig. 2 each link is slightly curved so that there is formed an air space between it and the ends of the two links in the next longitudinal row, as at i .

Having thus described the nature of the said invention and the best means I know of carrying the same into practical effect, I claim:—

1. A chain-grate link provided with means to receive supporting pins, said link being of uniform thickness throughout its length and, when in fuel supporting posi-

tion, being laterally convex toward one side of the grate and laterally concave toward the other side of the grate.

2. A grate chain comprising a plurality of links arranged side by side, each link being of uniform thickness throughout its length and provided with means for receiving connecting pins, the end portions of each of said links, being turned laterally from the body portion thereof, substantially as described, and for the purpose set forth.

3. A grate chain comprising a plurality of links arranged side by side, each link being of uniform thickness throughout its length and provided with means for receiving connecting pins, the end portions of each of said links, being turned laterally from the body portion thereof, and each link being provided with a driving tooth on one of its edges.

In testimony whereof I have signed my name to this specification.

WILFRED ROTHERY WOOD.
